FOUNTAIN PEN OR SIMILAR ARTICLE OF MANUFACTURE

Moses Fainberg and Bertrand M. Fainberg,
New York, N. Y.

Application June 29, 1949, Serial No. 3,612

Term of patent 14 years

(Cl. D74—17)

To all whom it may concern:

Be it known that we, Moses Fainberg and Bertrand M. Fainberg, citizens of the United States of America and residents of New York, county and State of New York, have invented a new, original, and ornamental Design for a Fountain Pen or Similar Article of Manufacture, of which the following is a specification, reference being had to the accompanying drawing, forming a part thereof.

In the drawing,

Fig. 1 is a front elevational view of a fountain pen, showing our new design;

Fig. 2 is a front view of the cap thereof;

Fig. 3 is front view of the fountain pen, without the cap; and

Fig. 4 is the front view of the fountain pen with the cap secured to bottom of the pen.

We claim:

The ornamental design for a fountain pen or similar article of manufacture, as shown.

MOSES FAINBERG.
BERTAND M. FAINBERG.
